(57) **CLAIM**

We claim the ornamental design for a showerhead assembly, as shown and described.

DESCRIPTION

FIG. 1 is a perspective view of a showerhead assembly showing our new design;

FIG. 2 is a front view of the present invention of FIG. 1.

FIG. 3 is a rear view of the present invention of FIG. 1.

FIG. 4 is a right side view of the present invention of FIG. 1.

FIG. 5 is a left side view of the present invention of FIG. 1.

FIG. 6 is a top view of the present invention of FIG. 1; and,

FIG. 7 is a bottom view of the present invention of FIG. 1.

The broken line showing portions of the showerhead is included for the purpose of illustrating and forms no part of the claimed design.

Patent No. D600,777 S

Patented: September 22, 2009

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Carl T. Whitaker, Berthoud, CO (US); Leland C. Leber, Fort Collins, CO (US); and Harold A. Luetgennas, Windsor, CO (US)

Signed and Sealed this Nineteenth Day of March 2013.
